COUNTING MECHANISM FOR SOLES AND
OTHER ARTICLES

Frederic E. Bertrand, Lynn, Mass., assignor to
United Shoe Machinery Corporation, Paterson, N. J., a corporation of New Jersey

Application January 25, 1932, Serial No. 588,570

11 Claims. (Cl. 235—98)

This invention relates to counting mechanisms. Such mechanisms are often known as counters, recorders, registers or, especially in the shoe machinery industry, as indicators.

The present invention is illustrated as embodied in a machine for reinforcing insoles of the type disclosed in Letters Patent No. 1,726,800, granted September 3, 1929, on an application of the present applicant, and more particularly in Figs. 1 to 6 of that patent. Such machines are commonly employed in shoe manufacturing for progressively pressing and securing a layer of cemented canvas or duck to an insole blank or body of leather and more particularly for securing the canvas in the inside angle formed between the insole body and the insole lip or channel flap.

Inasmuch as such a machine is often put out to the shoe-manufacturer on terms which involve the number of pairs of insoles which are reinforced by the use of the machine, it is important that a reliable record of that number be made and preserved. Accordingly, each such machine has usually been equipped with a counter operatively connected to a treadle which is depressed by the machine operator in order to separate the feed rolls of the machine when an insole to be reinforced is to be inserted between said rolls, as is fully explained in said Patent No. 1,726,800.

Under most operating conditions, when the insole rib extends round the forepart and through the shank of the insole but not round the heel, the treadle of the machine is depressed only once for each insole operated upon, with the result that the counting mechanism accurately registers the number of pairs of insoles passing through the machine.

However, under a variety of operating conditions which sometimes exist in different shoe factories, the treadle is depressed twice or more for each insole and, indeed, there is always liability that the treadle may be depressed either intentionally or unintentionally by the operator or some unauthorized person when no work is being operated on or unnecessarily in the operation of the machine on work.

Moreover, after an insole has passed through the machine, it is sometimes found that the canvas has not adhered fully to the lip at some particular place, as for an inch or two at the toe. In such a case, the operator replaces the insole in the machine and repeats the reinforcing operation along the limited portion of the insole which needs to be perfected or "cobbled." In so

replacing the insole, the operator depresses the treadle again. Moreover, in some types of insole, the lip is carried completely around the periphery including the heel portion and, in such case, the operator depresses the treadle not only when the insole is placed in the machine but also when it is removed therefrom. In all such cases where the treadle is depressed more than once for each insole, the counter, when operated by the treadle as above described, registers a number which is higher than the number of pairs of insoles actually and completely reinforced by the use of the machine.

Accordingly, it is an important object of the present invention to provide a counting mechanism which will be adapted to be associated with a machine for operating on soles and which will register accurately the number of soles or pairs of soles which pass through the machine but which will not register when there are merely accidental or additional depressions of the treadle or when partial operations of the kind above described are performed.

With this object, among others, in view the invention contemplates a counting mechanism which includes a counter or register proper and connections therefrom to a work engaging member, which, in the particular embodiment of the invention herein shown, is a roll which co-operates in the feeding of a sole or other article through a machine in which the counting mechanism is embodied. Preferably, and as herein shown, this feed roll is operated from the same actuator or driving means that operates the counter and the connections between this actuator and the feed roll include lost motion devices, such as an inclined slot and pin, which permit limited relative movement between the actuator and the roll in both a forward and in a reverse direction and which are so constructed and arranged that the counter is operated only after a predetermined relative movement in one direction between the roll and its actuator has been completed.

While this counting mechanism is herein described, by way of example, as embodied in a machine for reinforcing insoles, the invention is likewise adapted for use in counting other articles.

The invention will now be described in detail with the aid of the accompanying drawing which illustrates its preferred embodiment and then will be particularly pointed out in the claims.

In the drawing,
Fig. 1 is a front elevation, with some parts

shown in section, of a portion of an insole reinforcing machine equipped with such a counting mechanism;

Fig. 2 is a sectional plan along the line II—II
5 of Fig. 1;

Fig. 3 is a perspective view of the counter and
some of its operating mechanism;

Fig. 4 is a similar view of a detail of said mech-
anism, and

10 Fig. 5 is a sectional view of the connection be-
tween two shafts forming a part of the feeding
mechanism.

As already indicated, the illustrated reinforcing
15 machine, like that shown in said Patent No.
1,726,800, comprises a pair of feed rolls 20, 22 and
a pressure roll 24 which functions also as a feed
roll. The upper feed roll 20 is carried at the end
20 of a horizontal driving shaft 26 mounted in bear-
ings in a carrier 28 so that it may be moved to-
ward and away from the feed roll 22 which is
fixed to the main driving shaft 30 rotatable in
bearings in the machine frame indicated at 32.

The pressure roll 24 with its supporting and
driving mechanism is mounted in a bracket 36
25 which is guided for movement in a straight line
parallel to the axis of the main shaft 30. The
insole to be reinforced having a layer of canvas
laid thereon is inserted with its lip or rib and
the margin of the canvas between the feed rolls
30 20 and 22 and with the opposite face of the insole
next to the pressure roll 24. To facilitate the
insertion of the insole, the machine is provided
with a treadle by which the feed roll 20 may be
moved upwardly and the pressure roll 24 may be
35 moved laterally away from the feed roll 22, as
fully explained in said Patent No. 1,726,800.

Under usual conditions, these three feed rolls
are positively driven from a suitable source of
power to rotate at substantially the same periph-
40 eral speed but, according to the present invention
as already outlined, provision is made
through a lost motion connection between the
pressure roll and its driving mechanism or actuator
45 for a limited forward and reverse relative
movement between the pressure roll and said actuator
and such relative movement in one direc-
tion or the other is utilized to cause the counter
to register. The mechanism for thus actuating
50 the pressure roll includes a shaft 34 which may be
considered as the actuator and which is rotatable
in the carrier 36 as in the machine of said patent.
Fixed at one end of the shaft is a bevel gear
38 meshing with another bevel gear 40 fixed on
55 or formed as a part of a driving sleeve 42 sur-
rounding a shaft 44 rotatably and axially movable
in the carrier 36. This shaft has, at its upper
end as shown in Fig. 5, a tongue 46 which has a
sliding fit in a slot 47 at the lower end of a shaft
48 to the upper end of which the pressure roll 24
60 is fixed, this shaft 48 being mounted for rotary
but for no other movement relative to the carrier
36. Projecting radially from the shaft 44 is a
pin or roll 50 which has a running fit in a slightly
inclined cam slot 52 in the driving sleeve 42. A
65 coil spring 54 connected at its upper end to the
sleeve 42 and at its lower end to a collar 56 se-
cured to shaft 44 tends to maintain the roll 50 at
the lower end of the slot 52, as shown in Fig. 1,
but, when sufficient resistance to the rotation of
70 roll 24 is applied by the machine operator in hold-
ing back on the insole, as below explained, the
actuator 34, which operates to turn gear 40 in a
counter clockwise direction, will cause the roll
50 to move to the opposite end of the cam slot 52
75 against the resistance of spring 54 and thus move

the shaft 44 axially upward. A counter 60 of a
well-known commercial type is operated through
connections from shaft 44 which include a bar 62
fitting a groove 64 in collar 56. This bar is
5 mounted in an arm 66 of a bell crank lever, the
fulcrum 68 of which is journaled in a bracket 70
projecting downwardly from a cover 72 screwed to
a part of the carrier 36, the counter 60 being also
10 mounted on the bracket 70. The second arm 74
of the bell crank lever carries a spring pressed
pawl 76 which engages a ratchet wheel 78 mount-
ed for free rotation co-axially with the fulcrum
68 of the bell crank lever. This ratchet wheel has
15 twenty teeth 80 and has fixed to its outer face a
crank pin 82 to which is pivoted a link 84 also
pivotedly connected at its upper end to a pin 86 in
a crank arm 88 clamped to the actuating shaft 90
15 of the counter 60. For the purpose of the prelim-
inary setting up of the mechanism and specifically
in order to obtain a preferred angular relation
20 between the ratchet wheel 78 and the registering
wheels of the counter 60, this arm 88 is split, as
indicated at 92, so that it may be turned on shaft
90 and then clamped in adjusted position by a
screw 94. A spring pressed retaining pawl 96
25 prevents movement of the ratchet wheel in a
direction opposite to that indicated by the arrow
in Fig. 3.

It is considered desirable to employ a counter
which will register up to approximately one mil-
lion pairs of insoles but it is not important to
register less than ten pairs. Moreover, a counter
with six registering wheels is substantially more
expensive than one with five such wheels. Hence,
30 applicant finds it convenient to employ a counter
with only five wheels, and, therefore, showing
only five digits and to stamp a zero in line with
these digits on the frame of the counter as indi-
cated at 98 in Fig. 3. Accordingly, assuming
35 that the counter is originally set to register zero,
thereafter the digit 1 on the right wheel, as indi-
cated in Fig. 3, will appear only after the
ratchet wheel 78 has made one complete rotation
which will be after ten pairs of insoles have been
40 fed through the machine. Moreover, the highest
45 number that this counter will register will be
999,990. Obviously, however, other types and
sizes of counters can be used in carrying out this
invention.

Although the manner in which the present
50 counting mechanism operates has been indicated
in the course of the above detailed description
thereof, it will now be set forth briefly.

Of course, the machine may be started and
stopped, if desired, for each insole passing through
55 the machine but most operators prefer to have
the machine, including rolls 20, 22, and 24, run
continuously while a large number of insoles are
successively operated upon. Just before insert-
ing an insole in the machine, the operator, by de-
pressing a treadle, moves rolls 20 and 24 away
60 from roll 22 and then places the lip of the insole,
with its layer of reinforcing canvas, between the
rolls 20 and 22 with the feather lying against the
end face of roll 22 and with the leather base of
65 the insole toward the pressure roll 24. Upon re-
leasing the treadle, springs cause the rolls 20
and 24 to move toward roll 22 to grip the insole
with a substantial but yielding pressure tending
70 to feed the insole forwardly. Inasmuch, however,
as these rolls are rotating at full speed, whereas
the operator is holding the insole in her hand or
hands and must make sure that the lip and
feather of the insole are located in just the proper
75 position between the rolls, the operator holds back

on the insole at first so that there is a considerable slippage of all three of these rolls with relation to the insole. Moreover, by reason of the pin and slot connection 50, 52, which constitutes a lost motion device, the roll 24 will slip rotatively relative to the rolls 20 and 22, and the shaft 44 will turn forwardly more slowly than the sleeve 42, at the same time winding up the spring 54 so that the shaft 44 will move axially and upwardly and so that the upper, or left, end of slot 52 will finally be brought against the pin or roll 50, after which the shafts 44 and 48, and the roll 24, as well as rolls 20 and 22, will be positively driven forwardly by their driving mechanism until the insole is removed from between the feed rolls. The distance that the margin of the insole will be fed forwardly, against the force exerted by the operator tending to hold it back, before the upper end of slot 52 comes into engagement with pin 50, will depend on various factors, such as the length of the slot, the strength of spring 54, the position of roll 24 relative to roll 20, the degree of inward pressure of the roll 24 against the sole and the skill of the operator in correctly and quickly locating the insole in proper position between the rolls, but applicant has found that the objects of the invention are successfully attained by so proportioning these machine parts that the margin of the insole shall be fed forward a linear distance of not over five inches before the end of the slot 52 engages the pin 50 and with such an adjustment the counter 60 will be operated only once for each insole which passes through the machine even when insoles suitable for the smallest sizes of shoes are operated on, but this distance may be substantially varied without impairing the accuracy of the count.

By the time that the end of the slot 52 has thus come into engagement with the pin 50, the pawl 76 will have moved idly clockwise, as illustrated in Fig. 3, from engagement with the radial face of one tooth of ratchet wheel 78 into a position between the radial faces of the next two teeth. Indeed, to compensate for wear, backlash and other possible irregularities, it is desirable to have the pawl move at this point in the cycle a distance considerably more than that between the radial faces of two adjacent teeth but this movement must be less than the distance between one tooth and the second tooth beyond.

When the operation upon the insole has been finished and upon the removal of the insole from the machine, the resistance to the rotation of roll 24 in the direction opposite to that indicated by the arrow in Fig. 1 will have been removed and the roll with its shaft and shaft 44 will be turned in a reverse direction with relation to the sleeve 42 by spring 54 so that the slot 52 moves over the pin 50 until the latter comes into engagement with the lower or right end of the slot, as indicated in Fig. 1. This relative rotary movement will move the shaft 44 axially and downwardly and cause the pawl 76 to turn the ratchet 78 a distance equal to the pitch of the ratchet teeth, viz. 18°. When this operation has been repeated and a total of twenty insoles or ten pairs have been operated on, the unit registering wheel of the counter 60 will be turned one step so that ten pairs will be registered by the counter.

Furthermore, in the practical use of the present machine it has been found that when a "partial" or "cobblering" operation of the character above described is performed the linear travel of the insole is substantially less than five inches so that

the pin 50 travels so short a distance along the slot 52 that the pawl 76 in its idle movement will travel less than the distance between two successive teeth on the ratchet wheel 78 and, therefore, the counter will not register such a partial operation. 5

Moreover, it is evident that for the proper operation of this counting mechanism there must be a limited relative rotation alternately in opposite directions between the shaft 44, connected to the pressure roll 24, and the sleeve 42, positively geared to the feed roll 22, and that this relative rotation occurs in one direction at the beginning of an operation on an insole when the peripheral surface of the roll 24 travels more slowly than the peripheral surface of the roll 22 and in the other direction just as or after the insole has been removed from the machine when the roll 24 travels faster than roll 22. 10 15

Having thus indicated the object and nature of the invention and having described in detail one embodiment of it, what I claim as new and desire to secure by Letters Patent of the United States is:

1. In a sole machine, a pair of feed rolls and a pressure roll, all normally operated at substantially the same peripheral speed, in combination with a shaft to which the pressure roll is fixed, a second shaft rotatable with but movable axially relatively to said first shaft, power driving means for said pressure roll including a sleeve surrounding said second shaft, a pin and inclined slot connection between the latter and said sleeve through which relative rotation of said second shaft and said sleeve alternately in opposite directions effects axial movements in opposite directions of said second shaft, a counter for registering the number of pairs of soles passing through the machine, and connections from said second shaft to the counter through which said axial movements operate the counter. 20 25 30 35 40

2. In a sole machine, a pair of feed rolls and a pressure roll, all normally operated at substantially the same peripheral speed, in combination with means for driving the pressure roll which permits a limited movement of that roll relative to said feed rolls, said means including an axially movable shaft, a pin thereon and a part having an inclined slot in which the pin travels, a counter, and connections between the latter and said shaft for operating the counter while such limited movement is taking place and for thereby registering the number of soles passing through the machine. 45 50 55

3. In a machine for performing an operation on a piece of work, the combination of a work engaging member, a counter, and means for driving said member and for operating said counter, including a shaft, a pin thereon and a part having an inclined slot cooperating with the pin so constructed and arranged that said counter is operated only while the pin is moving along the slot. 60 65

4. In a machine for performing an operation on a piece of work, the combination of a work feeding member, an actuator and connections from said actuator to said member which permit relative movement between said actuator and said member and through which said member is operated to feed the work, said connections including a sleeve provided with an inclined slot and an axially movable shaft having a projecting pin 70 located in and arranged to travel along said slot, a counter, and co-operating connections between said counter and said shaft through which the counter is operated only during said relative movement. 75

5. In a machine for performing an operation on a piece of work, the combination of a work engaging member, an actuator and connections from said actuator to said member which connections include two co-operating elements movable alternately in opposite directions both rotatively and axially with relation one to the other and which connections first permit limited relative movement between said actuator and said member and then cause them to be driven synchronously, a counter, and operating connections between the latter and one of said co-operating elements so constructed and arranged that the counter is operated during said relative axial movement in one direction but is not operated during said synchronous driving.

6. In a machine for performing an operation on a piece of work, the combination of a work feeding member, an actuator and operating connections from said actuator to said member including a sleeve provided with a cam slot and a shaft having a projecting pin located in and arranged to travel along said slot which connections permit limited relative forward and reverse movements alternately between said actuator and said member, a counter, and operating connections including a pawl and ratchet between the counter and said shaft so constructed and arranged that the counter is operated only while said pin is traveling along said slot in one direction.

7. In a machine for performing an operation on a piece of work, the combination of a work feeding member, a counter, and driving means for both said member and said counter including an axially movable shaft, a pin thereon, a part having an inclined slot co-operating with said pin during relative forward and reverse movement between said pin and said part, said driving means for the counter including a spring and other connections between said counter and said shaft.

8. In a mechanism for counting pieces of work, the combination of a work feeding member, a counter, and actuating mechanism for both said

member and said counter including a driving shaft, a driven shaft, a pin and cam slot connection and a spring between said two shafts to permit relative rotary and relative axial movement alternately in opposite directions between said feeding member and said driving shaft, said movement taking place in one direction against the resistance of said spring and in the other direction through the force of said spring.

9. In a machine for performing an operation on a piece of work, the combination of a work feeding member, a counter, a shaft operatively connected to said member and to said counter, and means for rotating the shaft and for moving it axially to operate both said member and said counter.

10. In a machine for performing an operation on a piece of work, the combination of a work feeding roll, a shaft from which the roll is driven, a pin projecting from said shaft, a sleeve having an inclined slot along which said pin is movable, means for rotating said sleeve and thereby imparting axial movement to said shaft, a spring connecting said shaft and sleeve and tending to hold said pin at one end of the slot, a counter, and connections therefrom to said shaft through which the counter is operated during an axial movement of said shaft.

11. In a counting mechanism, the combination of a work feeding roll, a shaft to which the roll is fixed, a second shaft rotatable with but movable axially relatively to said first shaft, a pin projecting from said second shaft, a driving sleeve surrounding said second shaft and having therein a cam slot along which said pin travels, a spring connecting said second shaft and said sleeve and tending to hold the pin at one end of the slot, a counter, and connections including a pawl and ratchet between the counter and said second shaft so constructed and arranged that the counter is operated through said spring only during the travel of the pin toward the said end of the slot.

FREDERIC E. BERTRAND.
